(57) **CLAIM**

The ornamental design for a vehicle instrument panel, as shown and described.

DESCRIPTION

FIG. 1 is a frontside perspective view of the vehicle instrument panel;

FIG. 2 is another perspective view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a rearside perspective view thereof;

FIG. 9 is another perspective view thereof; and,

FIG. 10 is a rear view thereof.

In the drawings, the broken lines depict environmental subject matter only and form no part of the claimed design.

1 Claim, 10 Drawing Sheets
